DESCRIPTION

FIG. 1 is a perspective view of a clamp tie showing our new design;

FIG. 2 is a top plan view thereof;

FIG. 3 is a bottom plan view thereof;

FIG. 4 is a front elevation view thereof, the rear elevation being identical thereto; and,

FIG. 5 is a right side elevation view thereof, the left side elevation being identical thereto.

The break lines shown in FIGS. 1-4 indicate that the straps have no specific length; said break lines form no part of the claimed design.

The broken lines in FIGS. 2 and 3 illustrate environment only and form no part of the claimed design.
